[57] CLAIM

The ornamental design for a pearl necklace or similar article, substantially as shown.

DESCRIPTION

FIG. 1 is a fragmentary front elevational view of a pearl necklace or a similar article, showing my new design portions of the chain being omitted for convenience of illustration;

FIG. 2 is a fragmentary rear elevational view thereof; FIG. 3 is a side elevational view thereof, the opposite side being symmetrical; and

FIG. 4 is a top plan view thereof the chain being omitted for convenience of illustration.

FIG. 1.

FIG. 4.

FIG. 2.

FIG. 3.
